UNITED STATES PATENT OFFICE.

GEORGE W. SIMMONS, OF ST. LOUIS, MISSOURI.

CYCLOMETER ATTACHMENT FOR TYPE-WRITING MACHINES.

No. 813,525.

Specification of Letters Patent.

Patented Feb. 27, 1906.

Application filed July 17, 1905. Serial No. 270,168.

To all whom it may concern:

Be it known that I, GEORGE W. SIMMONS, a citizen of the United States, and a resident of St. Louis, Missouri, have invented certain new and useful Improvements in Cyclometer Attachments for Type-Writing Machines, of which the following is a specification.

This invention relates to improvements in a cyclometer attachment for type-writing machines; and it consists of the novel arrangement, construction, and combination of parts, as will be fully hereinafter described and claimed.

The object of my invention is to provide an ordinary type-writing machine with a cyclometer for registering the number of times the carriage has been operated daily.

A further object of my invention is to keep record of work done by the stenographer.

20 Figure 1 is a perspective view of my invention shown in position and in connection with the escapement of a type-writing machine. Fig. 2 is a top plan view of the same.

Referring to the drawings in detail, 3 indicates the frame of a type-writing machine, and 4 the rack which meshes with pinion 4'.

5 indicates a cyclometer of ordinary and common construction which is attached to the frame 3 of the type-writing machine by 30 means of the bracket 6. The mechanism of the cyclometer is controlled by the shaft 7, upon which is mounted a ratchet-wheel 8 and a gear-wheel 9. To the gear-wheel 9 is pivotally connected a pawl 10, its tooth contacting 35 with the teeth of the ratchet 8 and held in position by the spring 11. The ratchet-wheel 8 is rigidly connected to the shaft 7, while the gear-wheel 9 is loosely mounted thereon and meshing with the gear-wheel 12, rigidly 40 mounted upon the escapement-shaft 13 of the type-writing machine.

The operation of my invention is as follows: While the type-writer is being operated the escapement, during the manipulation of each 45 key, has a step-by-step motion, which will operate the gear-wheel 12, which in turn operates the gear-wheel 9, and during this operation the pawl 10, moving with the gear-wheel 9 in the direction indicated by the arrow, allowing said pawl to slide over the ratchet-teeth without affecting or operating the cyclometer mechanism. When the car-

riage has reached its destination, the operator, replacing the carriage to the starting-point, will cause the gear-wheel 12 and 11 to move 55 in opposite directions, thereby allowing the pawl 10 to engage with the ratchet-wheel 8 and revolve the shaft, which in turn operates the cyclometer mechanism, advancing it one number.

I have shown my attachment as applied to a Remington type-writer of modern style and construction; but it is obvious that the device may be attached to different styles and constructions of type-writing machines.

I do not desire to limit myself to this precise method of attaching the cyclometer to the type-writing machine, as it will be necessary in applying the cyclometer to different makes of type-writers to add an additional 70 gear-wheel and a differently-constructed support, whereby the cyclometer is attached to the machine.

Having fully described my invention, what I desire to claim and secure by Letters Patent is—

1. A cyclometer attachment for type-writing machines comprising a cyclometer; a bracket supporting the same on the frame of the type-writer; a shaft communicating with 80 and operating the cyclometer mechanism; an escapement mechanism of a type-writer, and means between the escapement mechanism and the cyclometer-shaft for operating the cyclometer, substantially as set forth.

2. In a cyclometer attachment for type-writers, the combination of a cyclometer provided with a shaft arranged to be operated thereby, a gear-wheel loosely mounted thereon, the escapement mechanism of the type-writer provided with a shaft and gear-wheel arranged to mesh with the loosely-mounted gear-wheel, and pawl-and-ratchet means between the loosely-mounted gear-wheel and the cyclometer-shaft, whereby the latter is 95 operated when the escapement mechanism moves in one direction, but remains at rest when moved in the other direction.

3. A cyclometer attachment for type-writing machines comprising a cyclometer suitably supported to the frame of the type-writer; a shaft communicating with the internal mechanism of the cyclometer; a ratchet-wheel rigidly mounted upon said shaft; a

gear-wheel loosely mounted upon said shaft
an escapement mechanism of a type-writer,
a shaft operated by the escapement mechanism
provided with a gear-wheel arranged to
mesh with the loosely-mounted gear-wheel,
and a pawl connected to the latter arranged
to operate the cyclometer-shaft in one direction.

In testimony whereof I have signed my
name to this specification in presence of two ^{to}
subscribing witnesses.

GEORGE W. SIMMONS.
